US00D754738S

(12) United States Design Patent
Park et al.

(10) Patent No.: US D754,738 S
(45) Date of Patent: * Apr. 26, 2016

(54) DISPLAY SCREEN OR PORTION THEREOF WITH ICON

(71) Applicant: Samsung Electronics Co., Ltd., Suwon-si (KR)

(72) Inventors: Yong-Man Park, Yongin-si (KR); Min-Sun Kim, Seongnam-si (KR)

(73) Assignee: SAMSUNG ELECTRONICS CO., LTD., Suwon-Si, Gyeonggi-Do (KR)

() Term: 14 Years

(21) Appl. No.: 29/479,877

(22) Filed: Jan. 21, 2014

(30) Foreign Application Priority Data

Sep. 17, 2013 (KR) 30-2013-0048046

(51) LOC (10) Cl. 14-04

(52) U.S. Cl.

(57) CLAIM

The ornamental design for a display screen or portion thereof with icon, as shown and described.

DESCRIPTION

The FIGURE is a front view of a display screen or portion thereof with icon, showing our new design.

In the drawings, the dot-dash broken lines are for the purpose of showing a display screen or portion thereof with icon that forms no part of the claimed design.
